UNITED STATES PATENT OFFICE.

WOLF ARBETTER, OF CHELSEA, MASSACHUSETTS, ASSIGNOR TO ARBETTER FELLING MACHINE COMPANY, OF BOSTON, MASSACHUSETTS, A CORPORATION OF MAINE.

PRESSER-FOOT.

996,192.

Specification of Letters Patent. Patented June 27, 1911.

Application filed June 18, 1906. Serial No. 322,131.

To all whom it may concern:

Be it known that I, WOLF ARBETTER, a citizen of the United States, residing at Chelsea, county of Suffolk, and State of 5 Massachusetts, have invented an Improvement in Presser-Feet, of which the following description, in connection with the accompanying drawing, is a specification, like letters on the drawings representing like 10 parts.

This invention relates to a novel presser-foot for use in machines for felling or making a blind stitch, machine such as shown and described in Patent No. 830,699, grant- 15 ed September 11, 1906. The patent referred to shows a presser-foot having guiding edges, and a throat-closing device to control the size of the throat in the presser-foot to correspond with the thickness of the stock 20 or material being bent upwardly into said throat by a bender as said material is being stitched by a blind stitch to the body material.

Herein the presser-foot is provided with 25 an edge-lifter that lifts the edge of the material, a lining that is to be blind-stitched to the body material on which the lining is superimposed, that said edge may be maintained upturned near the delivery end of 30 the edge-lifting device so that the point of the needle located wholly above the presser-foot and work-support may get under said lifted edge when making blind stitches. The edge-lifter is so constructed that it may 35 be moved longitudinally of the foot and thus raised to provide for a seam in the lining.

The presser-foot herein shown is further 40 provided at its under side with a detachable notched plate forming the rear edge of the throat.

Figure 1 in side elevation represents my 45 improved presser-foot the fabric or material under the foot being shown in section on the line x , Fig. 3; Fig. 2 is an end elevation of the foot looking at Fig. 1 from the right; Fig. 3 is a plan view; Fig. 4 is a section on the line x' , Fig. 3, and Fig. 5 is an under-side elevation of the parts shown in Fig. 2.

50 In the drawings, A represents a presser-foot, it having rising therefrom a suitable shank A' that in practice will be attached to a presser-foot-carrying bar common to said patent. The foot is cut through from its top to its bottom side to form a throat b,

and the under side of the foot is recessed to receive the nearly circular part of a throat-closing device d^6 common to said patent, it being pivotally sustained by a screw a in the presser-foot, said throat-closer having 60 a projecting shank, and suitable locking means represented as a spring-pressed pin a' , see Fig. 2, carried by the foot, co-acting with notches in the arm of the throat-closer to lock the same in its adjusted position. 65 The under side of the foot is provided with a groove in which is inserted a block a^3 notched at its inner end, the said block being held in place by a screw a^4 . The upper side of the block sustains the needle as it 70 passes out of the material on its forward movement during the formation of the stitch, and the foot is scooped out or countersunk at a^5 to provide room for the completion of the needle's movement and for 75 the swing of the needle laterally between the straight and the diagonal thrusts which occur in making a stitch.

The material being stitched together comprises usually what I shall designate body 80 material b' , which may be the material of which a rain-coat or other garment is made, and its lining or facing b^2 , the edge of the facing being blind stitched to the body material, and in doing this the body material 85 will be raised at intervals as provided for in said patent by a bender.

The stitch-forming mechanism to be used with the presser-foot herein shown, as well 90 as the work-support, will be the same as provided for and fully described in said application.

The foot A, see Fig. 2, is slotted at its edge to receive a lip e extended from the edge-lifter e' shaped to present a guiding groove 2 and preferably a finger-piece e^2 . The lip e has a slot 4 shown by dotted lines that is entered by two pins 3 carried by the foot, and by engaging the finger-piece e^2 , the edge-lifter may be moved longitudinally 100 on the foot, and thus raised from the work owing to the upward inclination of the toe of the presser foot. The edge lifter is slid to the right viewing Figs. 1 and 3 whenever a seam in the lining or facing enters the guiding groove 2 that acts on the inturned edge of the lining.

The positions of the needle in stitching are represented by dotted lines in Fig. 3, one dotted line showing the diagonal thrust 110

or that thrust of the needle which passes through the material in a direction diagonal to the line of feed, and the other the straight thrust or that thrust of the needle which 5 passes through the material in the direction of the line of feed, the needle at the straight thrust entering only the body material, and at the diagonal thrust entering only the upturned edge of the lining or facing which is held lifted by the edge lifter so that the point of the needle may get well under the edge.

I find it of great advantage to lift the 15 edge of the lining or infolded material through the agency of the edge-lifter herein described, and the stitching done is much better and more closely resembles hand blind stitching than when the edge b^2 is not uplifted as herein provided for.

20 I have secured to the upper side of the presser-foot by screws g a guard g' , it crossing the presser-foot at right angles and being of a length to extend considerably beyond the side edges of the presser-foot. The 25 guard g' is shown in my pending application, Serial No. 322,132, filed June 18, 1906, and is therein claimed.

Having fully described my invention, what I claim as new and desire to secure by 30 Letters Patent is:—

1. A presser foot for a blind stitch sewing machine provided with an opening through which the work is presented to the needle and having a recess on its upper face to receive a needle passing thereover, an edge 35 lifter to direct the edge of an upper layer

of the work above the bottom of the presser foot at said opening, and means for raising the edge lifter independently of the presser foot when desired to allow the passage of 40 seams or other irregularities.

2. A presser foot for a blind stitch sewing machine provided with an opening through which the work is presented to the needle and having a recess on its upper face to receive a needle passing thereover, and a notched plate inserted in the bottom of the presser foot and constituting the bottom of 45 said recess at the rear of said opening and means for removably attaching the said 50 plate to the presser foot.

3. A presser foot for a blind stitch sewing machine provided with an opening through which the work is presented to the needle and having a recess on its upper face to receive a needle passing thereover, a forwardly and upwardly inclined toe slotted at its edge, an edge lifter slidably mounted in 55 said slot and acting to direct an edge of an upper layer of the work above the bottom of the presser foot at said opening, said edge lifter being raised to allow the passage of seams or other irregularities by sliding the same forward on the inclined toe.

In testimony whereof, I have signed my 60 name to this specification, in the presence of two subscribing witnesses.

WOLF ARBETTER.
